COMBINED LAUNDRY CABINET AND
IRONING BOARD

John B. Brochu, Beverly, Mass.

Application July 6, 1948, Serial No. 37,225

7 Claims. (Cl. 38—126)

1

My invention relates to improvements in combined laundry cabinets and ironing boards, and it has for its primary object to generally improve upon the structure disclosed in my prior Patent No. 1,029,585, dated June 18, 1912, with particular reference to the means for supporting the ironing board in its operative horizontal position.

More specifically, the present invention contemplates a novel foldable or collapsible supporting means for an ironing board, shelf, table or the like, which while adapted to rigidly support the same in operative position, will be readily foldable into a compact space when the board or shelf is swung to its inoperative position, the nature of said support parts and their arrangement being such that it is not necessary to disconnect any of the same when the board is to be moved to inoperative position.

Additionally, the invention has for an object to furnish a novel cabinet or other wall-provided housing for the ironing board when it is not in use, and likewise for the collapsed ironing board support.

Other objects and advantages of the invention will become apparent as the description proceeds.

It is further to be understood that the invention resides in certain novel features of construction, combination and arrangement of the various parts without reference to their employment in connection with an ironing board, or for that matter, with a cabinet or other wall-providing structure.

In accordance with the requirements of the patent statutes, I have demonstrated in the accompanying drawings the presently preferred example of my inventive concept. Needless to say, however, the invention is susceptible of other mechanical expressions within the spirit and scope of the subject matter claimed hereinafter.

In the drawings, wherein the same reference characters have been used to designate the same parts throughout the several views,

Fig. 1 is a rear perspective view of a combined ironing board and laundry cabinet embodying my invention, the ironing board being shown in its "out of use" position;

Fig. 2 is a front end elevation illustrating the ironing board swung out horizontally in its position for use;

Fig. 3 is a vertical sectional view through the cabinet portion of the device and showing the ironing board in its operative position, the board, per se, being shown in side elevation;

Fig. 4 is a view similar to Fig. 3, but showing the ironing board in its inoperative position, the

2

laundry cabinet being shown in vertical section;

Fig. 5 is a fragmentary view, partly in section and partly broken, showing portions of the ironing board support elements after they have been moved from the Fig. 3 position to admit of the ironing board assuming the "out of use" position disclosed in Fig. 4;

Fig. 6 is a detailed view showing the prop carried pin 35 of Figs. 3 and 5 seated in the notch of the cabinet carried guide for holding the parts in the Fig. 3 position; and

Fig. 7 is a detailed view illustrating the slideable interconnection between the ironing board supporting prop element 31, 32 and the intermediate prop member 27 of Figs. 2, 3 and 5.

Referring to the drawings by reference characters, numeral 8 indicates generally the upstanding laundry cabinet which has the top 9, the bottom 10, and side walls 11.

Figures 3 and 4 illustrate the back wall 13 as having the co-extensive rearward bend 13a adjacent the top wall 9 to provide the offset wall portion 13b which connects with the top 9 of the cabinet. As will be appreciated from an inspection of Figs. 1, 3 and 4, the side walls 11 extend rearwardly beyond the plane of the rear wall 13, 13a, 13b, so as to cooperate therewith in providing the rear recess 14 which when the prop elements of the ironing board are in the inoperative position of Fig. 4, serve to house the same, and also to substantially house the ironing board 13, as indicated in Fig. 1.

The rear wall recess 14 is co-extensive in width with the cabinet 8 and is open at its bottom as indicated in Figs. 3 and 4; and it will also be noted from an inspection of said figures, that the cabinet is supported at each bottom corner by feet 12.

Access to the interior of the cabinet 8 is had through the door 15 at the front thereof, Figs. 3 and 4 illustrating the door 15 as being hinged as at 16 to one of the side walls 11.

The interior of the cabinet is provided with a number of vertically spaced transverse shelves 17, indicated in Figs. 3 and 4, and these may be and preferably are supported on angles 17a secured to the side walls 11. The shelves 17 may be permanently secured to the angles 17a in any preferred manner, or they may be simply rested thereon so as to be removable. The shelves 17 form a convenient depository for articles ironed or to be ironed, and the cabinet 8 may be employed as a convenient storage place for clean linen when a linen closet is not available.

Coming now to the ironing board, it will be

noted upon reference to Figs. 2 and 3 that the board 18 is pivoted as at 19 to the upper end of the rear wall offset 13b, by means of what may be a conventional hinge having one leaf 19a secured to the ironing board and the other leaf 19a secured to the rear surface of the rear wall offset 13b.

When the ironing board 18 is not in use, its rear end projects vertically upward above the plane of the cabinet top 9 as indicated in Fig. 1, it being noted that the board has shoulders 18a overlying the rear part of the top 9, and terminating preferably substantially in line with the side edges of said top wall 9 so as to provide a symmetrical appearance. What, in Fig. 1, would be the front surface of the projecting portion of the board (and which rests upon the top 9 of the cabinet when the board is in use as in Fig. 1) may be finished to conform with the finish of the cabinet and lends itself to use as a convenient means for supporting a mirror. Also, the rear edge of the ironing board 18 may be ornamenteally shouldered adjacent each edge, as indicated at 18b, to improve the appearance of the cabinet and ironing board assembly when the board is not in use.

The outer or work surface of the ironing board 18 at its rear end (see Figs. 1 and 3) is provided with the iron rest or support 20 which has its rear end pivoted as at 21 to the mid-portion of a bracket-provided arch 22 having the mounting seat 22a which is secured to the working surface of the board adjacent its rear end.

The iron rest 20 has projecting from its under surface adjacent its free end, the plate or other support 20a which is adapted to rest upon a metal liner 23a in what is shown as a rectangular recess 23 formed in the board 18. The provision of the metal lined recess 23 serves to protect the ironing board 18 from the heat of an iron on the rest 20, particularly in the event that the user should forget to disconnect the current to the iron.

It will be apparent that the top of the cabinet provides a substantial support for the rear end of the ironing board 18 when it is in use as indicated in Figs. 2 and 3. The collapsible prop means for supporting the outwardly projecting portion of the ironing board 18 will now be described.

The collapsible prop or supporting means for the projecting portion of the ironing board 18 beyond the rear wall of the cabinet 8 comprises a link 25 which is pivoted as at 24 (see Figs. 3 and 4), to the under surface of the projecting portion of the ironing board 18. The inner end of the link 25 is pivoted as at 26 to the outer end of a much longer link 27 whose inner end is pivoted as at 28 to the rear wall 13 of the cabinet adjacent the bottom 11 thereof.

Fig. 7 illustrates the elongated link or prop element 27 as having its side edges turned inwardly as indicated at 27a, to provide the guideway 29 for receiving the head 30 of a T extension which projects from the lower edge of a cross-member 31 (see Figs. 2 and 3) which connects the side legs 32 of a floor engageable prop. Fig. 2 illustrates the prop providing links 25, 27 which have connection with the ironing board 18 and cabinet 8, as being disposed midway between the legs 32 of the floor engaging prop referred to.

As illustrated in Fig. 2, the legs 32 of the floor engaging prop are angle-form to provide flanges 32a adjacent to and parallel with plane of the inner surfaces of the side walls 11 of the cabinet.

Projecting inwardly from the leg flanges 32a are flange portions which may have their edges reverted upon themselves as indicated in Fig. 2, for strengthening purposes, and also to receive the inturned ends of the cross-piece 31 which are indicated at 31a. The ends 31a of the cross-piece 31 may be welded or otherwise secured to the floor engaging legs 32.

On the subject of the pivots 24, and 28, (see Fig. 2) they may take the form of staple-like members, as indicated, and in the case of the pivot 28 its ends would receive nuts indicated at 28a in Fig. 3 when, as is preferable, the cabinet is of metal.

Still referring to the floor engaging prop having the legs 32, it will be noted from an inspection of Figs. 2 and 3, that the inner ends of said legs 32 are connected by a second cross-piece 34.

Referring now to Figs. 3, 5 and 6, it will be noted that the flange 32 of each leg of the floor engaging prop has a laterally projecting pin 35 adjacent its inner end and carrying at the outer surface of said flange and spaced therefrom, the concentric disk or rotatable anti-friction element 36. Each anti-friction element or disk 36 is adapted to normally work in a vertical guideway 37, provided by the respective inturned side flanges 38 of a guide member 39.

There are, of course, two guide members 39, one secured to the rear portion of one side wall 11 of the recess 14, and the other secured to the other side wall thereof. Screws or the like 40 may be availed of for securing the guide members 39 to side walls 11, and they project through the plate extensions 39a and 39b of said guide members 39.

Fig. 5 illustrates the rear guide-providing flange 38 of the guide member 39 as being provided, adjacent its lower end, with an outwardly inclined notch 41, which when the ironing board is in the operative position shown in Figs. 2 and 3, is adapted to receive the adjacent disk carrying pin 35, so as to lock the prop incorporating supporting means of the ironing board in its operative position, as will be presently explained.

In addition to the sliding connection with the cabinet through the pin and guide connection 35, 37, at each side, the legs 32 of the floor engaging prop member 32, 31, 34, have the link connection 42, with the lower plate extensions 39b of the respective guide members 39 (see Figs. 2 and 3). Each of the side links 42 is pivoted as at 42 to the flange 32a of the adjacent floor engaging prop-leg 32, while the inner end of said link 42 is pivoted as at 41 to the plate extension 39b of the related guide 39.

As will be observed from an inspection of Figs. 1, 3, and 4, one rear edge of the side wall 11 of the cabinet has the retaining element 46 for maintaining the ironing board in its inoperative position substantially within the recess provided at the rear of the cabinet 8. The ironing board retaining means as indicated in Fig. 1, takes the form of a strip or cleat 46 which is pivoted to the side wall edge as indicated at 47, and has the operating finger piece 48.

The working surface of the ironing board 18 may be provided at its rear end with the transverse rod 45 whose inturned ends are secured to the board so that the major portion of the rod will be spaced away from the same, and provide a support for suit hangers, or the like.

The operation of the ironing board supporting means will be summarized as follows:

Referring to Figs. 1 and 4, which illustrate the ironing board in its inoperative position, and as

suming that it is desired to put the board in the operative Fig. 3 position, it is only necessary to swing the ironing board 18 clockwise about its pivot 19. When this is done, the pivot 26 which connects the links 25 and 27 of the board supporting top moves downwardly and outwardly from the Fig. 4 position. Likewise, the bearing disks 35 at the inner ends of the floor engaging prop legs 22 move downwardly in the guide 31 from the dotted line position indicated in Fig. 6, 10 until the pins 35 which carry the anti-friction disks 36 engage in the respective notches 41 of the rear flange 38 of the guide 39.

It is to be understood that in the Fig. 3 position of the ironing board support, the pins 35 15 are engaged in their respective notches 41. While the foregoing is happening, that is to say, while the prop elements are moving to the Fig. 3 position from the Fig. 4 position, the T-projection 30 (Fig. 7) of the lower cross member 31 is moving downwardly in the guide 29 provided by the flanges 27a of the lower elongated board supporting link member 27.

When the parts have assumed the Fig. 3 position, it will be obvious that pressure on the extended portion of the ironing board 18 will be transmitted through the prop links 25, 27 to the cross member 31 of the floor engaging prop 32, 32, 34. This floor engaging prop 32, 32, etc., is prevented from moving, firstly, by engagement of the side pins 35 in the notches 41, and secondly, by the bracing action of the link 42.

To release the ironing board from its Fig. 3 position, it is necessary to move the prop element 32, 32, 31, 34 counter-clockwise about 43 as a pivot to disengage the pins 35 from the notches 41. When this has been done the reverse of the previously described operation takes place by simply swinging the ironing board counter-clockwise about its pivot 19, as viewed in Fig. 3.

Having thus described my invention, what I claim is:

1. The combination with a support; of an ironing board hinged to the top thereof, and adjustable to extend vertically behind the support, links pivoted to the rear portion of the support, legs pivoted to said links adjacent the outer ends of the latter, opposed vertically extending guideways at opposite sides of said support, a laterally extending pivot pin carried by each of said legs adjacent the rear end of same and slidably engaging in the adjacent guideway, a folding prop pivoted at one end to the under side of said ironing board and at the other end to said support, said prop comprising sections pivotally connected intermediate their ends, a cross member connecting said legs and engaging one of said prop sections to sustain the same when the ironing board is in operative position, and means for retaining said pins against movement in said guide slots and said legs in fixed position when the ironing board is in operative position.

2. The combination with a support; of an ironing board hinged to the top thereof, and adjustable to extend vertically behind the support, links pivoted to the rear portion of the support, legs pivoted to said links adjacent the outer ends of the latter, opposed vertically extending guideways at opposite sides of said support, a laterally extending pivot pin carried by each of said legs adjacent the rear end of same and slidably engaging in the adjacent guideway, each of said guideways having a seating notch for the associated leg pin and receiving the same when the ironing board is in operative position.

ironing board is in operative position, a folding prop pivoted at one end to the under side of said ironing board and at the other end to said support, said prop comprising sections pivotally connected intermediate their ends, a cross member connecting said legs and engaging one of said prop sections to sustain the same when the ironing board is in operative position, and the weight of said ironing board acting through said prop forcing said leg pins into said seating notches.

3. The combination with a support; of an ironing board hinged to the top thereof, and adjustable to extend vertically behind the support, links pivoted to the rear portion of the support, legs pivoted to said links adjacent the outer ends of the latter, opposed vertically extending guideways at opposite sides of said support, a laterally extending pivot pin carried by each of said legs adjacent the rear end of same and slidably engaging in the adjacent guideway, a folding prop pivoted at one end to the under side of said ironing board and at the other end to said support, a cross member connecting said legs and engaging said prop to sustain the same when the ironing board is in operative position, and means for retaining said pins against movement in said guideways and said legs in fixed position when the ironing board is in operative position.

4. The combination with a support; of an ironing board hinged to the top thereof and adjustable to extend vertically behind the support, links pivoted to the rear portion of the support, legs pivoted to said links adjacent the outer ends of the latter, opposed vertically extending guideways at opposite sides of said support, a laterally extending pivot pin carried by each of said legs adjacent the rear end of same and slidably engaging in the adjacent guideway, a folding prop pivoted at one end to the under side of said ironing board and at the other end to said support, said prop comprising sections pivotally connected intermediate their ends, a cross member connecting said legs and engaging one of said prop sections to sustain the same when the ironing board is in operative position, said cross member having an interengaging slidable connection with said leg section, and means for retaining said pins against movement in said guide slots and said legs in fixed position when the ironing board is in operative position.

5. The combination with a support; of an ironing board hinged to the top thereof, and adjustable to extend vertically behind the support, links pivoted to the rear portion of the support, legs pivoted to said links adjacent the outer ends of the latter, opposed vertically extending guideways at opposite sides of said support, a laterally extending pivot pin carried by each of said legs adjacent the rear end of same and slidably engaging in the adjacent guideway, each of said guideways having a seating notch for the associated leg pin and receiving the same when the ironing board is in operative position, a folding prop pivoted at one end to the under side of said ironing board and at the other end to said support, said prop comprising sections pivotally connected intermediate their ends, a cross member connecting said legs and engaging one of said prop sections to sustain the same when the ironing board is in operative position, said cross member having an interengaging slidable connection with said leg member, and the weight of said ironing board acting through said prop forcing said leg pins into said seating notches to retain the ironing board in operative position.

6. The combination with a support; of an ironing board hinged to the top thereof, and adjustable to extend vertically behind the support, opposed guide track-providing members secured to said support, links pivoted to said members below the guide-providing portions thereof, legs pivoted to said links adjacent the outer ends of the latter, a laterally extending pivot means carried by each of said legs adjacent the rear end of same and slidably engaging the proximate guide means, a folding prop pivoted at one end to the under side of said ironing board and at the other end to said support, said prop comprising sections pivotally connected intermediate their ends,

a cross member connecting said legs and engaging one of said prop sections to sustain the same when the ironing board is in operative position, and means for retaining said pivot means against movement in said guides and said legs in fixed position when the ironing board is in operative position.

7. The combination set forth in claim 6, and each of said guides having means for locking said leg-provided pivot means against movement when the ironing board is in operative position.

JOHN B. BROCHU.
